Primary Examiner — Omeed Agilee*(74) Attorney, Agent, or Firm* — Stephen D. Carver(57) **CLAIM**

The ornamental design for a support insert for surgery bed, as shown and described.

DESCRIPTION

FIG. 1 is a front isometric view of a support insert for surgery bed showing the left side configuration;
FIG. 2 is a rear right isometric view thereof;
FIG. 3 is a rear left isometric view thereof;
FIG. 4 is a top plan view thereof;
FIG. 5 is a bottom plan view thereof;
FIG. 6 is a left side elevation view thereof;
FIG. 7 is a right side elevation view thereof;
FIG. 8 is a front elevation view thereof;
FIG. 9 is a rear elevation view thereof;
FIG. 10 is a front isometric thereof in a state of use attached to a surgery bed;
FIG. 11 is a front isometric view of the support insert for surgery bed showing the right side configuration;
FIG. 12 is a rear right isometric view thereof;
FIG. 13 is a rear left isometric view thereof;
FIG. 14 is a top plan view thereof;
FIG. 15 is a bottom plan view thereof;
FIG. 16 is a left side elevation view thereof;
FIG. 17 is a right side elevation view thereof;
FIG. 18 is a front elevation view thereof;
FIG. 19 is a rear elevation view thereof; and,
FIG. 20 is a front isometric thereof in a state of use attached to a surgery bed.
The dashed lines in the drawings depict environmental subject matter and form no part of the claimed design.
